INVENTOR,
H. Lund Smith,
BY
John L. Smith,
ATTORNEY

UNITED STATES PATENT OFFICE.

HENRY LUND SMITH, OF PATERSON, NEW JERSEY.

AUTOMOBILE TIMING MECHANISM.

Application filed January 7, 1922. Serial No. 527,873.

To all whom it may concern:

Be it known that I, HENRY LUND SMITH, a citizen of the United States, residing at Paterson, in the county of Passaic and State 55 of New Jersey, have invented certain new and useful Improvements in Automobile Timing Mechanisms, of which the following is a specification.

The commutator of a Ford automobile 10 motor is usually held revolubly against an upright face of the fixed motor structure by a blade which overlaps the commutator and is held to said structure by a stud projecting therefrom and a nut on the stud. There is 15 no means to limit the rotation of the commutator in the direction to advance the spark excepting the stop against which abuts the member which, through a link, rotates the commutator, and if this link becomes bent 20 or distorted, as it frequently does, the commutator will stand displaced out of the extreme advanced position to which it is supposed to be set when said member abuts its stop. The object of this invention is to provide means for both holding the commutator 25 revolubly against said face of the fixed motor structure and limiting directly its rotative movement in one direction, as in the direction to advance the spark of the motor, the same to be simple in construction, reliable in operation and adapted to be applied to any existing Ford automobile motor by using said stud and nut as the means to secure it in place.

30 In the drawings,

Figure 1 is a front elevation of sufficient of a Ford automobile motor containing my invention to illustrate the same;

Figure 2 is a plan of what appears in 40 Fig. 1;

Figures 3 and 4 are views like Fig. 1, illustrating two different modifications; and

Fig. 5 is a plan of what appears in Fig. 4. 45 *a* is the rotary commutator arranged to bear against an upright face of the fixed structure *b* of the motor of a Ford automobile, and *c* is the link, pivoted to the stud *a'* of the commutator, by which the latter is 50 connected to the aforesaid member (not shown) for turning the commutator. The said stud *a'* forms a stop on the commutator, as will appear.

The usual Ford motor has a bolt *d* whose threaded end *d'* protrudes forwardly beside 55 the commutator and forms a fixed stud; on it is the nut *e*.

On this stud *d'* and under the nut *e* I secure the aforesaid means for both holding the commutator revolubly against the mentioned upright face of the structure *b* and limiting directly its rotative movement in one direction, to wit, in the direction to advance the spark.

Referring, first, to Figs. 1 and 2: Said 65 means is a plate in the form of a bifurcated arm *f*, one extension or finger *f'* of which is bent inward toward the structure *b* and has its free end cut off square and lying in the path of movement of the stop *a'* of the 70 commutator and the other extension or finger *f''* of which is bent away from said structure and overlaps the commutator, having a centering lug *f'''* which engages in the usual socket provided in the outer face of 75 the commutator. The arm *f* is penetrated by the stud *d'* and held fixed by the nut *e* screwed thereon. Thus the commutator is 80 kept against the face of the structure *b* and the rotation thereof to advance the spark is directly determined, to wit, by contact of stop *a'* with the stop afforded by the free end of the finger *f'* of said arm *f*. Any possible tendency of the arm to turn on *d'* 85 as an axis is in this case resisted by the engagement of lug *f'''* in the socket of the commutator.

Referring to Fig. 3: Here the arm is formed by two separate blades *g* and *h*. The blade *g* has its free end cut off square and arranged in the path of movement of stop *a'*. The other blade *h* overlaps the commutator and has a centering lug *h'* engaged in the socket in the outer face of the commutator. Both blades are penetrated by stud *d'* and held fixed by the nut *e* screwed thereon. Blade *g* is kept against possible tendency to turn on *d'* as an axis by having upstanding cheeks *g'* between which blade *h* fits, blade *h* being kept against such turning by the engagement of its lug *h'* in the socket of the 100 commutator.

Referring to Figs. 4 and 5: Here the arm is again formed by two blades *i* and *j*. Blade *i* has its free end cut off square and arranged 105 in the path of movement of stop *a'*. The

other blade *j* overlaps the commutator and has a centering lug *j'* engaged in the socket in the outer face of the commutator. Both blades are penetrated by stud *d'* and held fixed by the nut *e* screwed thereon. Blade *i* is kept against possible turning on *d'* as an axis by having a two-arm claw *i'* which is bent around a projection *b''* of structure *b* and bears against the same.

- 10 By my invention it is only necessary to remove the usual blade which overlaps the commutator and holds the same against structure *b*, being itself held by stud *d'* and nut *e*, and substitute the improved arm, 15 which in any form thereof herein shown is extremely simple and inexpensive to manufacture and very effectively performs the double service of keeping the commutator up to its bearing against said structure and 20 properly centered and forming a stop directly limiting the rotating movement of the commutator in the direction to advance the spark.

Having thus fully described my invention,

what I claim as new and desire to secure by 25 Letters Patent is:—

1. In combination, the fixed motor structure, a commutator revolvable against an upright face thereof, securing means including a stud rigidly projecting from said face beside the commutator, and means, held rigid by said securing means and penetrated by the stud, to hold the commutator against said face and directly limit the rotation of the commutator in one direction. 35

2. In combination, the fixed motor structure, a commutator revolvable against an upright face thereof and having a stop, securing means including a stud rigidly projecting from said face beside the commutator, and an arm held rigid by said means and penetrated by the stud and overlapping the commutator and holding the same against said face and having a stop in the path of movement of the first stop. 40 45

In testimony whereof I affix my signature.

HENRY LUND SMITH.
